UNITED STATES PATENT OFFICE

LEWIS EDWIN EAKIN, OF BURDETT, KANSAS

GRAIN LIFTING DEVICE

Application filed March 30, 1931. Serial No. 526,367.

This invention relates to an improved grain lifting device in the nature of an attachment adapted for use on the platform of a cutter bar equipped harvesting machine.

I am aware of the fact that various types of grain lifting and dislodging devices have been patented, and are in use to aid in lifting dropping and fallen grain, in a manner to elevate the grain to a point to be conveniently 5 and effectively severed by the cutting mechanism.

In developing the present improved grain lifting device, I have provided a structure which, to my mind, will better fulfill the requirements of an appliance of this class because of its peculiar construction and arrangement of parts, because said parts have been especially selected and mechanically correlated to form a device capable of accomplishing the grain lifting operation in a more dependable and satisfactory manner.

In the drawings:—

Figure 1 is a view showing the complete grain lifting device in elevation and applied 15 to the platform of a combine or harvester.

Fig. 2 is a top plan view of the structure seen in Fig. 1.

Fig. 3 is a bottom plan view thereof.

Fig. 4 is a perspective view of a renewable 20 and removable panel.

Fig. 5 is a combined perspective view of two distinguishable parts of the under strap structure.

Fig. 6 is a vertical or transverse section 25 taken on the line 6—6 of Fig. 1.

Fig. 7 is a perspective view of the substantially V-shaped carrier frame for the panel.

Fig. 8 is a section similar to Fig. 6.

Fig. 9 is a further detail section, taken on 30 the line 9—9 of Fig. 1.

One of the most important parts of the improved device is the hingedly mounted substantially V-shaped panel accommodating frame, denoted by the numeral 10 in Fig. 7. 35 I have found it practical and expedient to construct this from a single length of wire of appropriate strength to provide an upper arm 11 and a lower arm 12, and the curved bight portion is distinguished by the numeral 13.

The arm 12 is rigidly fastened to a strap 14 forming a part of the hinge construction, and it will be noted that the forward extremity of this strap 14 is curved and fastened in place as indicated at 15 to cooperate 55 with the bight portion 13 in forming a sort of a shoe to ride along the ground 16 as indicated in Fig. 1.

On its under side, the strip 14 is provided with a shoulder forming lug 17 which serves 60 a purpose to be hereinafter described. The arm 11 is slightly longer than the arm 12, and is bent partly as indicated at 18 to aid in maintaining the panel 19 in place. The extending extremity 20 of this arm forms a 65 handle to facilitate application and removal of the panel. The panel is in the nature of a V-shaped wooden board having a marginal groove 21 in which the arms 11 and 12 are seated. 70

This frame structure 10 as seen in Fig. 7, and the panel 19 as represented in Fig. 4, forms the principal forward and downwardly extending part of the lifting device, and this device is hingedly mounted on the platform 22 of the harvester. 75

I now call attention to the numeral 23 which designates a stationary strap riveted or otherwise fastened to the under side of the platform, and terminating near the front end of said platform. This strap 23 cooperates with the strap 14 in that the adjacent ends are formed to provide a hinged joint such as is indicated at 24. 80

The numeral 25 represents a hanger bracket carried by the intermediate portion of a strap 23 and provided with a guide pulley 26, over which an adjacent portion of the retention cable 27 is trained. This cable is attached at its inner end to a coiled spring 28 anchored on the adjacent end of the strap 23. Then the cable is passed through a guide eye 29 on the bolt 30 and through a second guide eye 31 on the lug 17. The front end of the cable is anchored to the front end portion of the strap 14 as indicated at the point 32. This cable, spring and pulley arrangement are designed to swing the entire frame and its panel down to a point to cause the shoe 23 to ride 95 in contact with the ground 16. 100

Means is provided to limit the downward swinging of the shifting device, and this preferably comprises an arm 33 held in place by the bolt 30, underlying and bridging the hinge 24 and having its free end portion in a position to engage behind the shoulder 17. Thus, the lug 17 abutting the arm 33 serves to limit the downward swinging motion of the forwardly and downwardly inclined lifting device.

At the same time, upward bobbing and swinging is allowed to minimize resistance against the travel of the shoe 15. This upward swinging motion is, however, controlled by the spring pulled cable 27.

Consequently the spring and its cable tends to urge the shoe 15 into gliding contact with the ground, but the shoe is prevented from becoming embedded in the ground by the co-acting stop elements 17 and 33.

Particularly do I wish to emphasize the arrangement embodying the resilient V-shaped frame 10 into which the panel board 19 is removably snapped, and retained in place. Then too, I place stress on the idea wherein the lower arm 12 of this frame is attached to the bar or strap 14 allowing this bar to reinforce the frame, and permitting the bar to have the additional function of a long leaf in the hinge construction. Moreover, the bent terminal 15 of the bar 14, allows it to partly shield the curved bight 13 and to at the same time form a free gliding ground engaging shoe.

The use of the elongated stationary leaf 23 of the hinge is important, in that this constitutes a mounting for the bracket 25 carrying the guide pulleys as well as provides anchorage for the spring 28. Moreover, the bolt 30 serves to secure the strap 23 in place, carries the guide eye 29 and fastens one end of the stop arm 33 in its operative position.

Consequently all of the parts have been carefully selected and organized to provide a complete structural arrangement which will operate efficiently and which is subject to repair when the board 19 becomes unduly warped. A constantly straight hingedly mounted free gliding grain lifting device is believed to be desirable to facilitate grain cutting.

It is thought from the foregoing description that the advantages and novel features of the invention will be readily apparent.

It is to be understood that changes may be made in the construction and in the combination and arrangement of the several parts, provided that such changes fall within the scope of the appended claims.

Having thus described my invention, what I claim as new is:

1. In a structure of the class described in combination, a portable support including a platform, a frame hingedly mounted thereon, a removable panel mounted in said frame,

together with a reinforcing strap attached to the lower arm of the frame and having its frontal portion formed to provide a ground engaging glide shoe.

2. In a grain lifting device of the class described, a platform, an elongated movable hinged leaf pivotally mounted at its inner end on said platform and having its forward end curved to provide a ground engaging shoe, a substantially V-shaped frame having its lower arm attached to said hinged leaf, said frame and partly nested in the shoe, and a removable panel board provided with a marginal groove in which the bight and arm portions of the frame engage.

3. In a grain lifting device of the class described, a platform, an elongated movable hinged leaf pivotally mounted at its inner end on said platform and having its forward end curved to provide a ground engaging shoe, a substantially V-shaped frame having its lower arm attached to said hinged leaf, said frame and partly nested in the shoe, a removable panel board provided with a marginal groove in which the bight and arm portions of the frame engage, the upper arm of said frame being bent intermediate its ends to engage the adjacent inner end of the panel to aid in maintaining the panel in place to simultaneously form a handle to facilitate application and removal of the panel.

4. In a structure of the class described in combination, a platform, a stationary strap secured to the under side of said platform, a relatively movable strap hingedly connected to the front end of said stationary strap, a grain lifting device connected to said movable strap, a spring attached to the under side of the platform and a cable attached to said spring, guide means for said cable, the front end of said cable being connected to the front end portion of said movable strap.

5. In a structure of the class described in combination, a platform, a stationary strap secured to the under side of said platform, a relatively movable strap hingedly connected to the front end of said stationary strap, a grain lifting device connected to said movable strap, a spring attached to the under side of the platform and a cable attached to said spring, guide means for said cable, the front end of said cable being connected to the front end portion of said movable strap, said movable strap being provided adjacent said hinge with a lug forming a stop shoulder, and an arm attached to said first-named strap bridging the hinge and having its free end engageable with said lug to limit the downward swinging movement of said grain lifting device.

6. In a structure of the class described in combination, a platform, a stationary hinge strap fixedly attached to the under side of the platform, a swingably mounted companion

strap hinged to the front end of said first-named strap and projecting beyond the platform, a grain lifting device mounted on said movable strap, a stop lug carried by the intermediate portion of the movable strap, an arm attached at one end to said fixed strap and having its free end engageable with said lug, a pulley equipped bracket carried by and depending from the intermediate portion of 5 said first-named strap, a cable attached at its outer end to the front end portion of the movable strap, guide means for the intermediate portion of the cable, a portion of said cable being trained over said pulley, and a coiled 10 spring anchored at one end to the inner end of said first-named strap, said cable being connected with the opposite end of said spring.

In testimony whereof I affix my signature.
